Term of patent 14 years

(Cl. D26—1)

FIG. 1

FIG. 2

FIGURE 3

FIGURE 4

FIGURE 1 is a front perspective view of a carrying case for electronic equipment and the like embodying my new design;

FIGURE 2 is an end elevational view thereof;

FIGURE 3 is a view similar to FIGURE 1 illustrating a modified form of carrying case;

FIGURE 4 is an end view of the embodiment shown in FIGURE 3.

The dominant portions of the design are illustrated by the solid line representations of the drawing. The undisclosed end view in each embodiment is the same as the illustrated end view and the back of each of the embodiments is the same as the front thereof except for the broken line face portions.

I claim:

The ornamental design for a carrying case for electronic equipment and the like, substantially as shown and described.
